ABSTRACT

A deflection yoke with four compensation coils which are provided at the core inside which a pair of horizontal deflection coils are mounted and act on the magnetic flux generated from said horizontal deflection coils to generate a compensation field which makes the horizontal deflection field pin cushion fields at both right and left areas of the beam scanning range and a barrel field at the middle area of the range.

DEFLECTION YOKE

BACKGROUND OF THE INVENTION

The present invention relates to the deflection yoke to be employed in the picture tube with the so-called delta gun type in which three electron guns are positioned respectively at the vertexes of an equilateral triangle.

The conventional television set employing this type of the picture tube is provided with a convergence device to converge three electron beams into the same hole of a shadow mask.

However, various misconvergences which are presumed to result from the deflection field of the deflection yoke appear on the screen of the picture tube in spite of the convergence being performed as specified in actual reception of a color television.

Of these misconvergences, the misconception referred to as "S-ing" clearly appears on a 110° - deflected wide angle color TV picture tube.

The S-ing convergence is such that, as shown in FIG. 8, electron beams R and G diverge 180° from each other on a line parallel with horizontal axis X in reference to electron beam B even though three electron beams B, R and G are completely converged on vertical axis Y and horizontal axis X which pass through center O of screen of the picture tube. This misconception is referred to as the "S-ing misconception" because divergence appears in the form of letter S.

It is known that this S-ing phenomenon can be reduced by making the deflection field of the deflection yoke assume a pin cushion distribution at both side areas and a barrel distribution at the middle area of the electron beam scanning range in the emission of the electron beams at the screen side as shown in FIG. 9. Therefore, it is proposed in conventional picture tubes to partly cut away the horizontal deflection coil as shown in FIG. 10 if horizontal deflection coil D of the deflection yoke is of the saddle type and as shown in FIG. 11 if the horizontal deflection coil is toroidally wound.

However, if this approach is employed, the deflection yoke is disadvantageous because the distribution of the winding of the deflection coil is complicated, mass production of the deflection yoke is difficult, the chipped portion is formed in parallel with the winding of the deflection coil and the field distribution obtained due to the chipped portion is the same at any cross section of the deflection field whereby the field distribution cannot be adjusted.

The saddle type deflection coil is usually employed as the horizontal deflection coil for a television. Since this type of coil is made up by forming a saddle - shaped clearance in the dies for winding wire and filling the clearance with an electric wire, it is disadvantageous because it is difficult to form the chipped portion as shown.

The present invention provides a deflection yoke free from the disadvantages described above.

SUMMARY

The deflection yoke according to the present invention is comprised of a pair of the toroidal type or saddle type vertical deflection coils, a pair of the toroidal type or saddle type horizontal deflection coils, a core provided with said deflection coils, and four toroidal type or saddle type compensation coils provided at said

core, wherein said compensation coils are overlapped on part of a pair of horizontal deflection coils and are arranged so as to produce magnetic fluxes which compensate the horizontal deflection magnetic field generated by the horizontal deflection coils, said compensation coils being respectively arranged symmetrically at both sides of each horizontal deflection coil in reference to the center line of the horizontal deflection coil and, at the same time, being positioned so that the deflection magnetic field of the horizontal deflection coils is compensated to the pin cushion fields at both side areas of the electron beam scanning range and to a barrel field at the middle area of the scanning range.

BRIEF DESCRIPTION OF THE DRAWINGS

The present invention is illustrated in detail by the accompanying drawings whereon:

FIG. 1 is a plan view of a deflection yoke according to the present invention,

FIG. 2 is a magnified cross sectional front view along line II-II in FIG. 1,

FIG. 3 is an explanatory view of horizontal deflection magnetic field formed by this deflection yoke,

FIGS. 4 and 5 are plan views of the core illustrating the arrangement of compensation coils of this deflection yoke.

FIG. 6 is a circuit diagram of the compensation coil showing the other embodiment of this deflection yoke,

FIG. 7 is a diagram showing the waveform of the current to be supplied to the compensation coils shown in FIG. 6,

FIG. 8 is an explanatory view of the S-ing misconception by the conventional deflection yoke,

FIG. 9 is an explanatory view of the horizontal deflection magnetic field which compensates said S-ing misconception, and

FIGS. 10 and 11 are plan views illustrating conventional horizontal deflection coils.

DETAILED DESCRIPTION

Referring to FIGS. 1 and 2, there is shown deflection yoke 1 comprised of a pair of toroidal-type vertical deflection coils 2, a pair of saddle-type horizontal deflection coils 3, cylindrical core 4 around which said vertical deflection coils are wound, horn - shaped bobbin 5 which is mounted on said core and is provided with horizontal deflection coils 3 at its inside surface, four compensation coils 6 which are wound around core 4, clamp belt 7 which clamps the core, flange 8 attached to the rear part of the core and a plurality of clamping segments 9 extended from the flange toward the rear side along the neck of the picture tube (not shown).

In this embodiment, compensation coils 6 are wound together with said vertical deflection coils 2 around core 4. Each compensation coil 6 is symmetrically wound in reference to center line L of each horizontal deflection coil 3 and is arranged so as to be overlapped with part of each horizontal deflection coil 3.

Compensation coils 6 are made to generate magnetic fluxes which offset partly the magnetic flux from horizontal deflection coils 3; accordingly, the compensation coils generate the magnetic fluxes in the direction opposite the magnetic flux generated from horizontal deflection coils 3.

Such oppositely oriented magnetic fluxes can be easily generated from the compensation coils by reversing the winding direction of each compensation coil or by

selecting the direction of the current supplied to the compensation coils.

Referring to FIG. 3, there is shown a horizontal deflection magnetic field generated by horizontal deflection coils 3 and compensation coils 6.

If the magnetic fluxes from compensation coils 6 are not considered, the horizontal deflection magnetic field forms a conventional uniform magnetic field as shown with dotted lines. If the compensation magnetic fields of compensation coils 6 which are formed as shown with broken lines are applied to said magnetic field, part of the main deflection magnetic field from the horizontal deflection coils is offset by the compensation magnetic fields whereby the horizontal deflection magnetic field shows pin cushion distribution at both right and left side areas of the scanning range of the beams as shown with solid lines and a barrel distribution at the middle area of the scanning range. In other words, the horizontal deflection magnetic field which is desirable to compensate the S-ing misconvergence is formed in the magnetic fields generated by compensation coils 6.

The saddle type coil can be used as the compensation coils. In this case, four saddle type coils are arranged as in case of said embodiment.

If the compensation coils are wound in the reverse direction to the horizontal deflection coils, the horizontal deflection current can be supplied to compensation coils 6. In this case, the compensation coils can be connected in series and then can be connected in series to the horizontal deflection coils.

The ratio of the currents supplied to the horizontal deflection coils and the compensation coils can be predetermined; however, it is desirable to adjust the ratio of these currents by providing the current distributor in the circuit.

Thus, asymmetrical distortion due to error of the coil arrangement occurring in manufacturing the deflection yoke can be compensated.

If said current distributor can vary the ratio of the currents to be supplied to the compensation coils and the horizontal deflection coils during the scanning period, the distortion can be further rigorously compensated.

Compensation coils 6 need always not operate so as to offset the magnetic flux from horizontal deflection coils. If the horizontal deflection magnetic field shows a pin cushion distribution, the magnetic flux generated from compensation coils 6 can be superposed with the magnetic flux generated from the horizontal deflection coils.

In this case, the magnetic field generated by compensation coils 6 shows barrel distribution.

If the horizontal deflection magnetic field shows similarly the barrel distribution, the pin cushion distribution magnetic field may be formed by compensation coils 6.

However, as is well known, in case of the wide angle color picture tube, the integrated value of the horizontal deflection magnetic fields in planes intersecting at a right angle to the axial direction of the beam emission is made to cause a slight pin cushion type distribution to improve the convergence characteristic against divergence of three beams; accordingly, the horizontal deflection magnetic field may be actually a uniform magnetic field and a pin cushion distribution magnetic field.

If horizontal deflection coils 3 form a uniform magnetic field, compensation coils 6 are wound around core 4 as shown in FIG. 4.

Compensation coils 6 are positioned on outer side to be remote from each other at front side 31 of each horizontal deflection coil 3, that is, at the screen side of the picture tube, to offset the magnetic flux from the horizontal deflection coils and to form the deflection magnetic field as shown in FIG. 3, while it offsets the magnetic flux at the middle of the horizontal deflection field at rear side 32 of each horizontal deflection coil 3, that is, at the electron gun side of the picture tube and forms the pin cushion type magnetic field. On the other hand, if horizontal deflection coils 3 generate a pin cushion type magnetic field, compensation coils 6 are around core 4 so that they near each other at front side 31 of each horizontal deflection coil and are remote each other at rear side 32 as shown in FIG. 5.

In this embodiment compensation coils 6 are designed to generate magnetic fluxes in the same direction as horizontal deflection coils 3. Accordingly, the magnetic field formed by the horizontal deflection coils tend to show the barrel distribution at the front middle and the pin cushion distribution at the rear side area.

In this embodiment, the deflection yoke is advantageous because the aforementioned integration value of the horizontal deflection magnetic fields of deflection yoke 1 shows the pin cushion distribution, whereas it forms the deflection magnetic field at the screen side as shown in FIG. 9.

The deflection yoke according to the present invention is advantageous because the horizontal deflection magnetic field is compensated by compensation coils, the production of the deflection yokes is easy and the distribution of horizontal deflection magnetic field can be freely compensated.

Because said compensation coils cause the magnetic fields to act on the deflection magnetic field, they can compensate deflection distortion, which is different from the S-ing misconvergence, together with the S-ing misconvergence.

Compensation coils 6 shown in FIG. 6 are designed to compensate the S-ing misconvergence and, at the same time, to compensate the divergence position of three electron beams B, G and R. The following describes the divergence positions of three electron beams. As is shown from contemporary research, it is desirable for convergence without deterioration of the purity to diverge three electron beams so that the electron beams are respectively positioned at the vertexes of an equilateral triangle at any position on the screen of the picture tube. However, in case of the wide angle deflection picture tube, it is inevitable that the spot positions of three electron beams correspond to the vertexes of a scalene triangle at the positions near the top, bottom, right side and left side areas of the screen, due to the curvature of the screen. Accordingly, the deflection yoke is disadvantageous because the purity deteriorates due to convergence.

Four compensation coils 6 shown in FIG. 6 are divided into a pair of groups 6' containing two coils which are series - connected and each group is parallel - connected to power supply 10. These four compensation coils 6 are series - connected to another power supply 11.

If power supply 10 is the deflection current source and the compensation current which has large ampli-

tude at the initial stage and the final stage of vertical deflection period IV as shown in FIG. 7 and the same phase as the horizontal deflection current is supplied from other power supply 11, compensation coils 6 generate field f_1 shown with dotted lines and fields f_2 shown with broken lines. As described above, field, f_1 shown with dotted lines is effective to compensate the S-ing misconvergence, and fields f_2 shown with broken lines acts to shift electron beams G and R in the horizontal deflection magnetic field.

Accordingly, with fields f_2 , the positions of two electron beams G and R can be shifted in reference to beam B which is positioned in the vertical direction and thus the positions of three electron beams can be adjusted with the compensation current from power supply 11 so that the spots of three electron beams are positioned respectively at vertexes of an equilateral triangle on the screen of the picture tube.

For such adjustment, however, the positions of three electron beams should be pre-adjusted so that the spots of three electron beams are respectively positioned at the vertexes of an equilateral triangle at a certain area on the screen and at the vertexes of an isosceles triangle at the other area on the screen. In addition, this pre-adjustment can be easily done.

Either of said power supplies 10 and 11 may be the horizontal deflection current source and the rest of power supplies may be selected according to the purpose of compensation of distortions except for the S-ing misconvergence.

What we claim is:

1. A deflection yoke comprised of
  - a. a pair of vertical deflection coils,
  - b. a pair of horizontal deflection coils,
  - c. a core on which said deflection coils are mounted and
  - d. four compensation coils which are arranged symmetrically in reference to the center line of each horizontal deflection coil, wherein said compensation coils are overlapped on part of said horizontal deflection coils respectively and are arranged to generate magnetic fluxes which cause the main deflection magnetic field generated from said horizontal deflection coils to be adjusted to show pin cushion distribution at both right and left side areas of the beam scanning range and to show barrel distribution at the middle area of said range, said horizontal deflection coils adapted to generate a uniform main deflection magnetic field and said compensation coils adapted to generate compensation magnetic fluxes which flow in the direction opposite the magnetic flux of said main deflection magnetic field.
2. A deflection yoke according to claim 1 wherein a horizontal deflection source is connected to said compensation coils.
3. A deflection yoke according to claim 2 wherein a current distributor is provided to vary the ratio of the horizontal deflection current supplied to said compensation coils and said horizontal deflection coils.
4. A deflection yoke according to claim 3 wherein said compensation coils are connected in series and the serially connected compensation coils are further connected in series with said horizontal deflection coils.
5. A deflection yoke according to claim 1 wherein said compensation coils are remote from each other at

the front side of each horizontal deflection coil and closer to each other at the rear side of each horizontal deflection coil and are near to each other at the rear side of each horizontal deflection coil.

5. 6. A deflection yoke comprised of
  - a. a pair of vertical deflection coils,
  - b. a pair of horizontal deflection coils,
  - c. a core on which said deflection coils are mounted and
  - d. four compensation coils which are arranged symmetrically in reference to the center line of each horizontal deflection coil, wherein said compensation coils are overlapped on part of said horizontal deflection coils respectively and are arranged to generate magnetic fluxes which cause the main deflection magnetic field generated from said horizontal deflection coils to be adjusted to show pin cushion distribution at both right and left side areas of the beam scanning range and to show barrel distribution at the middle area of said range, said horizontal deflection coils being designed so that the main deflection magnetic field generated by said horizontal deflection coils presents pin cushion type distribution, said compensation coils being arranged so that the coils are near each other at the front side of each horizontal deflection coil and are remote from each other at the rear side of said horizontal deflection coil, said compensation coils being designed to generate magnetic fluxes which flow in the same direction as the magnetic flux of the horizontal deflection coils whereby the magnetic fields of said compensation coils is superposed on the main deflection magnetic field.
7. A deflection yoke comprised of
  - a. a pair of vertical deflection coils,
  - b. a pair of horizontal deflection coils,
  - c. a core on which said deflection coils are mounted and
  - d. four compensation coils which are arranged symmetrically in reference to the center line of each horizontal deflection coil, wherein said compensation coils are overlapped on part of said horizontal deflection coils respectively and are arranged to generate magnetic fluxes which cause the main deflection magnetic field generated from said horizontal deflection coils to be adjusted to show pin cushion distribution at both right and left side areas of the beam scanning range and to show barrel distribution at the middle area of said range, said four compensation coils being series — connected in a pair of groups respectively containing two coils, said coil groups being parallel — connected to one power supply, said four compensation coils being series — connected to another power supply, one of said two power supplies being adapted to cause said compensation coils to generate magnetic fields which make the main deflection magnetic field to show pin cushion distribution at both right and left side areas of the beam scanning range and barrel distribution at the middle area of said range and the other power supply being adapted to cause said compensation coils to generate magnetic fields which shift two of three electron beams except for a beam in the vertical direction in the horizontal deflection magnetic field.
